ROTARY DRILL MECHANISM

Application filed September 12, 1928. Serial No. 305,446.

This invention relates to rotary drill mechanism and has for its object to maintain predetermined pressure by the bit against the bottom of a well bore irrespective of the downward feed of the drill stem. More particularly the invention provides for maintaining a yieldable downward pressure by the drill bit, either by fluid pressure or gravity so that in the event of the bit suddenly breaking through a relatively hard formation it will be immediately lowered relative to its drill stem without waiting for corresponding downward feed of the stem, and will thus remain in operative engagement with the bottom of the bore for uninterruptedly continuing the drilling operation through any relatively soft stratum which may be encountered.

It is a further object of the invention to preferably utilize the column of circulating fluid in the string of drill pipe as the medium for providing a yieldable downward pressure on the drill bit; and to arrange the parts so that during normal drilling a predetermined pressure on the bit may be maintained by the weight of simply the string of drill pipe, with the yieldable pressure of either the circulating fluid or gravity functioning to lower the bit relative to its stem only when abnormal conditions, such as breaking through to a relatively soft stratum, are encountered.

It is a still further object of the invention to provide for downward movement of the bit with relation to its stem while maintaining the necessary rotary driving connection between the drill pipe and the bit; and the invention also provides for packing off this telescopic engagement between the stem and bit so as to prevent leakage of the circulating fluid.

It is a still further object of the invention to preferably arrange the telescopic engagement between the stem and bit so as to permit of the drill string being floated into the well bore, and to also provide for normal circulation of fluid during operation of the drill, with said circulating fluid preferably utilized as the means for maintaining the desired yieldable pressure on the bit.

It is a still further object of the invention to provide an efficient but inexpensive construction, and one which is extremely durable and simple in its operation.

Further objects of the invention will be readily understood from the following description of the accompanying drawings, in which:

Fig. 1 is a side elevation of the invention, partly broken away and showing the drill bit telescoped relative to its stem.

Fig. 2 is a similar view showing the bit projected downwardly relative to its stem.

Fig. 3 is an enlarged transverse section on the line 3—3 of Fig. 1.

Fig. 4 is an enlarged transverse section on the line 4—4 of Fig. 2.

Fig. 5 is a view similar to Fig. 2 but showing a modified construction.

Fig. 6 is a transverse section on the line 6—6 of Fig. 5.

The invention is applicable to any usual rotary drill bit, shown as a fish-tail bit 1, and the bit is adapted for suspension from a mandrel 2, either by a usual coupling 3 as shown in Fig. 1, or by an interposed string of drill pipe 4^a and a drill collar 40 as shown in Fig. 5, with the mandrel arranged for telescopic movement relative to a usual drill stem comprising the lengths of drill pipe 4. This telescopic engagement includes a rotary driving connection between the stem and bit, and for this purpose the mandrel 2 may be exteriorly splined as shown at 5, for engagement by cooperating interior splines 6 on an abutment sleeve 7 which is suspended from the string of drill pipe 4 by a usual coupling 8.

The splined mandrel 2 is of appreciably greater length than the sleeve 7 so as to provide for relative axial movement between the bit and its stem, and said relative axial movement may be limited in one direction by an abutment at the upper end of the mandrel adapted for impingement by shoulders 10 formed by the upper ends of the splines 6, and may be limited in the opposite direction by outwardly flaring the lower ends of splines 5 to form a shoulder 11, and correspondingly flaring the lower end of the bore of sleeve 7 and its splines 6 as shown at 12, so that when

100

the drill bit telescopes relative to the string of drill pipe as shown in Fig. 1, the weight of the string will be exerted through sleeve 7 against the shoulder 11 of the mandrel 2, for maintaining any predetermined pressure on the drill bit during the normal drilling operation.

Should the drill bit break through a relatively hard formation during the drilling operation, so that a predetermined downward feed of the drill pipe will no longer maintain the desired pressure of the bit against the bottom of the well bore, the pressure of the circulating fluid in the drill string is adapted to project the telescoped mandrel 2 from the drill stem as hereinafter explained and as shown in Fig. 2, or the weight of drill pipe 4^a suspended from the telescoped mandrel is adapted to project the mandrel as shown in Fig. 5, thereby maintaining the desired pressure of the bit against the bottom of the bore by either fluid pressure or gravity means.

This projection of the bit is limited by shoulders 10 striking the abutment at the upper end of the mandrel, the said abutment being shown as a wear-resisting collar 9 which is preferably yieldably mounted on the mandrel for absorbing the shock of the impingement. As an instance of this construction the mandrel 2 may project upwardly beyond its splines 5 as shown at 15, with the collar 9 received on said projection and resting upon the splines 5, and a yieldable means shown as a rubber sleeve 16 received on projection 15 and abutting against the collar 9, the yieldable sleeve 16 being preferably held in place by a coupling 17 which may be threaded on the upper end of the mandrel.

Packing is preferably mounted on the mandrel for packing off the telescopic engagement between the drill bit and its stem, and preferably comprises usual packing cups 19-20 reversely mounted so as to pack off in opposite directions. The coupling 17 may provide a mounting for the lower packing cup 19 which has its lip 21 extending downwardly and received over a suitable shoulder 22 on the coupling 17, and this packing cup may be held in place by a coupling 23 threaded onto coupling 17 and in turn forming a mounting for the upper packing cup 20 which seats on a shoulder 24 of the coupling 23, with its lip 21 extending upwardly and received over a cooperating shoulder 22 of either a collar 25 or a collar 25^a shown in Figs. 1 and 5 respectively, and which may be interchangeably threaded onto the end of coupling 23.

The mandrel 2 together with couplings 17-23 and collar 25 or 25^a have a circulating bore 27 communicating with the usual fluid discharge bore of the drill bit; and as shown in Fig. 5 the collar 25^a forms an open bore for the circulating fluid, while as shown in Fig. 1 the collar 25 supports a valve 30 which is adapted to close the bore 27 to the bore of the

string of drill pipe 4, it being understood that mandrel 2 together with abutment means 9-16 and couplings 17-23 and collar 25 or 25^a are adapted for free sliding fit in the drill pipe 4, while the packing 19-20 engages the bore of said drill pipe and thereby packs off between the drill bit and its stem, so that the entire column of circulating fluid in the string of drill pipe must flow through the bore 27 for discharge from the drill bit.

The valve 30 opens downwardly from its seat 31 which may be threaded into the upper end of collar 25, and below the valve the bore of the collar is preferably of stream-line section as shown at 32 for unobstructed flow of the circulating fluid past the open valve and thence downwardly through bore 27. The valve 30 is adapted for yieldable seating, and for this purpose its stem 33 may project through a guide 34 extending upwardly from the valve seat 31, with a spring 35 mounted on the stem between the guide and an abutment means shown as a nut 36 which is threaded on the upper end of the valve stem.

The spring 35 is comparatively strong, but will yield to permit opening of valve 30 responsive to the pressure of a column of fluid in the string of drill pipe, and as a result of this tendency of the spring to close the valve, together with the leak-proof connection provided by packing 20 between the drill bit and its stem, it will be seen that during the drilling operation the column of circulating fluid will exert appreciable pressure against valve 30 tending to project the drill bit beyond its stem, and will then flow past the open valve 30 and through bore 27 for discharge at the drill bit in usual manner. This yieldable pressure tending to project the drill bit is normally overcome by the weight of the string of drill pipe resting on shoulder 11 and maintaining the drill bit telescoped as shown in Fig. 1, but when for any reason the string of drill pipe no longer maintains the desired pressure on the bit, the yieldable fluid pressure against valve 30 projects the bit as shown in Fig. 2 and thus maintains the desired drilling pressure irrespective of the downward feed of the drill pipe.

It will also be noted that the upwardly closing valve 30 together with the leak-proof connection provided by packing 19 between the drill bit and its stem, will completely shut-off the bore of the drill pipe during lowering of the string into a well, and the column of fluid in the well below said closure means will thus provide for floating the string into the well.

In the modification of the invention shown in Fig. 5, wherein the open bored collar 25^a replaces the valve 30, a sufficient length of drill pipe 4^a is interposed between the bit 1 and the mandrel 2 so that the weight of this pipe will provide the desired pressure tending to project the drill bit beyond its stem.

This yieldable gravity pressure tending to project the drill bit is normally overcome by the weight of the string of drill pipe 4 resting on shoulder 11 and telescoping the parts 5 as previously described, and when for any reason the downward feed of pipe 4 is no longer sufficient to maintain the desired pressure on the bit, the weight of pipe 4^a projects the bit and thus maintains the desired drilling 10 pressure. Throughout the drilling operation the open bore 27 communicating with the bore of the drill pipe permits of free circulation of fluid for discharge at the bit.

I have thus provided extremely simple but 15 practical means for floating a string of drill pipe into a well and then exerting the weight of the string against the drill bit during normal drilling, with the pressure of the circulating fluid adapted to project the drill bit 20 beyond its stem and thus maintain the desired pressure on the drill, in the event of the downward feed of the drill pipe failing for any reason to maintain the said desired pressure on the drill bit; and I have also provided 25 a construction whereby yieldable pressure on the telescopic drill bit may be maintained simply by gravity means without utilizing the pressure of the circulating fluid, when such a simplified apparatus is preferred.

30 I claim:

1. In combination, a drill stem, a drill bit, a telescopic connection between the stem and bit, means for discharging a circulating fluid through the stem and bit, means operable by 35 the circulating fluid for yieldably projecting the bit relative to the stem, wear-resisting abutment means for limiting said projection of the bit, and means for cushioning said abutment.

40 2. In combination, a drill stem, an internally splined sleeve suspended from the drill stem, an externally splined mandril cooperating with the internally splined sleeve for relative telescoping of said parts, and means 45 for suspending a drill bit from the mandril, the mandril flaring outwardly at the lower ends of its splines so as to form a shoulder, and the lower end of the bore of the splined sleeve being correspondingly flared for abutment against said shoulder.

50 3. In combination, a drill stem, a mandril adapted to telescope in said stem, means for suspending a drill bit from the mandril, a wear-resisting collar on the mandril, cushioning means mounted on the mandril and abutting against the wear-resisting collar, a coupling connected to the mandril and abutting against the cushioning means, and an abutment on the drill stem adapted to engage 55 the wear-resisting collar for limiting projection of the mandril relative to the drill stem.

60 4. In combination, a drill stem, a drill bit, a telescopic connection between the stem and bit, means for yieldably projecting the bit relative to the stem, wear-resisting abutment

means for limiting said projection of the bit, and means for cushioning said abutment.

5. In a drill stem, relatively axially telescopic parts having a splined engagement, the end of said splined engagement flaring to 70 form abutment means for limiting relative axial movement of said telescopic parts.

6. In a drill stem, relatively axially telescopic parts, a wear-resisting collar slidable on one of said parts, cushioning means for 75 limiting sliding of the wear-resisting collar on said part, and an abutment on the other of said parts adapted to engage the wear-resisting collar for limiting relative axial movement of said telescopic parts.

7. In testimony whereof he has affixed his 80 signature.
